UNITED STATES PATENT OFFICE.

RICHARD HARLAND DICKINSON, OF FARNHAM, ENGLAND.

TWO-STROKE ENGINE.

Application filed November 27, 1920. Serial No. 426,729.

To all whom it may concern:

Be it known that I, RICHARD HARLAND DICKINSON, a subject of the King of England, residing at Farnham, in the county of Surrey, England, have invented certain new and useful Improvements in Two-Stroke Engines, of which the following is a specification.

This invention relates to internal combustion engines designed to work on a two-stroke cycle.

The improved engine is of the type in which one or more double-ended cylinders are employed, one end of the cylinder serving for the induction and partial compression of the charge and the other end for the further compression, the explosion and expansion of the gases.

According to the present invention, the working cylinder which is provided at the head end with a mechanically operated exhaust valve, is provided also towards its opposite end for the admission of the working charge with a transfer port communicating with the inlet port at this end, both these ports opening directly into a chamber containing the charge-inlet valve which is preferably mechanically operated. The exhaust valve is opened towards the end of the expansion stroke and before the piston uncovers the transfer port, and at the head end of the cylinder there may be provided a sparking plug or other means of ignition.

The charge induced into and initially compressed in the crank end of the cylinder is preferably of pure air, and the transfer of this compressed air serves to scavenge the working end of the cylinder in the known manner whilst the exhaust valve remains open. Fuel is then injected above the piston through an orifice in the cylinder wall and forms with the air therein the explosive mixture which is finally compressed and exploded. The injection of fuel is preferably effected by a mechanical pump arranged in a constant-level fuel reservoir in proximity to the fuel-injection orifice, as has already been proposed in connection with internal combustion engines.

The operation of both valves and fuel pump may be performed by suitable cam grooves provided upon the crank discs.

The invention is hereafter described with reference to the accompanying drawings in 55 which:—

Figure 1 is an end elevation of a single cylinder engine.

Figure 2 is a longitudinal section of the same.

Figure 3 is a face view of one of the crank discs.

Figure 4 is a detail in section on a larger scale of the preferred form of fuel injection pump.

Figure 5 is a similar detail of the piston-rod gland in the lower cylinder cover.

The cylinder *a* is provided at its head end *a'* with an exhaust valve *b* communicating with exhaust manifold *b'* and a sparking plug *c*, while the crank end *a''* of the cylinder is provided with an induction port *a''* and a transfer port *a'''* which communicate with a chamber *a''''* containing an inlet valve *d*. The piston *e* is of such depth as to bridge 75 the web separating the ports *a''* *a''''*, so that in the position shown in Figure 2 there is a free passage from beneath the piston through the induction port *a''* into the inlet valve chamber *a''''* and thence through the 80 transfer port *a'''''* into the cylinder above the piston.

A fuel injection orifice *f* is arranged in the cylinder wall above the transfer port, fuel being delivered through this orifice by 85 a pump *g* from the reservoir *h* after the piston has covered the transfer port *a'''''* in its upward movement.

The piston *e* is provided with a packing rings *e'* and is formed integral with a rod 90 *e''* connected at its lower end to a dummy piston or cross-head *i* reciprocating in a guide cylinder *j* co-axially aligned with the working cylinder *a*. A cover *j'* is secured between the cylinders, and carries a central 95 gland *j''* to prevent leakage around the piston rod. This gland is shown in Figure 5 as comprising two halves contracted by springs *j'''* and having interengaging fingers *j''''* at their abutting faces. The cross-head is fitted with a gudgeon pin *i'* on which is mounted the connecting rod *k*, of which the big-end *k'* engages the crank pin *l*. In the construction illustrated a built-up crank-shaft is shown consisting of 100 105 discs or internal flywheels *m* secured upon

axles m^3 rotating in suitable bearings n in the sides of the crank case o , the crank pin l connecting together the two crank discs m .

The discs m are provided on their outer faces (see Figure 3) with cam grooves m^2 which receive the roller-fitted extremities p' of the valve tappets p moving in guides p^2 and serving to operate the valves b d . The tappets are preferably adjustable and may be connected to the valve-stems b' d' by means of spring coils p^3 so as to close the valves mechanically. Springs b^2 d^2 of the usual type may however be provided to close the valves, either instead of or in addition to the positive connections between valves and tappets.

The inlet valve tappet has a projecting spur p^4 operating a push rod g' of which the upper end engages in a rocker arm g^2 adapted to depress the fuel injection pump plunger G^2 . These parts may also be positively connected, for example by ball or knuckle joints, so that the pump plunger is raised by the return of the inlet tappet, or a spring may be employed to raise the plunger.

The cam groove m^2 upon the inlet valve side is timed to open the inlet valve d to allow the ingress of fresh air through the opening d^3 in the side wall of the engine as soon as the rising piston e covers the transfer port a^4 , and since the fuel pump is operated by the same cam-groove, the injection of fuel will take place approximately at the same moment. The inlet valve closes as the piston reaches the upper end of its stroke, thereby allowing the fuel pump plunger to rise and take in a fresh charge in preparation for the next injection. The amount of this charge may be adjusted by a needle-valve g^4 controlling the port g^5 through which the liquid enters from the reservoir h , in which it is maintained at constant level by a float h' carrying a valve h^2 serving to regulate the supply from a pipe h^3 . The liquid delivered by the pump passes through a non-return valve f' in the pipe or chamber leading to the injection port f where it emerges into the cylinder through a suitable nozzle or sprayer.

The cam-groove m^2 upon the opposite crank-disc is timed to open the exhaust valve b before the piston e uncovers the injection orifice f , so that the exhaust has already begun when the transfer port a^4 is uncovered. The air compressed beneath the piston then passes through the transfer port and completes the scavenging of the gases, replacing them by a charge of air. The exhaust valve b closes as the piston rises to the level of the upper edge of the transfer port, at approximately the same moment as the inlet valve d opens, and the compression in the head end a' of the cylinder begins. Fuel injection from the orifice f takes place early in the

stroke and the fully compressed charge is ignited by means of the sparking plug c .

Any other means of ignition may be employed, and if desired the engine may operate on a Diesel or semi-Diesel cycle, the injection of fuel being in that case retarded to the end of the compression stroke.

The crank case o is shown fitted with a sump r containing a lubricating oil-pump r' which is operated by an eccentric r^2 upon the crank axle, and fitted with suction and delivery valves. A pipe s conducts the oil to the bearing n of the adjacent crank axle m^3 , where it enters a radial oil-passage s' communicating with a longitudinal duct s^2 extending to the crank pin l . A similar duct s^3 on the opposite side of the crank pin conveys the oil to the other bearing n and thence to a pipe s^4 leading to a regulator t on the wall of the guide cylinder. The regulator is provided with an adjustable screw or needle-valve t' which allows a suitable flow of oil through the orifice t^2 into the guide cylinder. The dummy piston u guiding the cross-head i in the latter is formed with a central well u' in which the oil collects, surplus oil escaping through holes u^2 on to the gudgeon pin cross-head bearing of the connecting rod k and finding its way through the crank case into the oil sump r . The boss below the gland j^3 is arranged to enter the well u' at the end of the up-stroke of the piston, thereby forcing oil through a passage e^3 in the piston rod to radial ducts e^4 delivering the oil to the outer periphery of the piston between the rings e' .

An oil-filler o^2 is provided on the side of the crank case for the introduction of lubricant and an oil gauge may be fitted in any convenient position.

The crank axles m^3 may be provided with oil-throwers m' to remove excess lubricant, which returns to the sump through suitable ducts.

A magneto v is shown mounted on a bracket v' upon the crank case and driven by chain or other gearing contained in the casing v^2 . A screw v^3 holds the magneto in position.

It will be understood that the invention is not limited to the details of the construction described and illustrated by way of example. Thus the engine may be provided with two or more cylinders, if desired.

Having thus described my invention, what I claim as such and desire to secure by Letters Patent is:—

1. A two-stroke engine comprising a cylinder, a piston reciprocable within said cylinder, one end of said cylinder forming the working chamber, the other end of said cylinder forming the pump chamber, an exhaust valve in said working chamber, an inlet port in said pump chamber, a transfer port adjacent to said inlet port, a passage

- connecting said ports, means for admitting air only through said inlet port, and means for carburetting said air after compression in said pump chamber.
- 5 2. A two-stroke engine comprising a cylinder, a piston reciprocable within said cylinder, one end of said cylinder forming the working chamber, the other end of said cylinder forming the pump chamber, an exhaust valve in said working chamber; an inlet port in said pump chamber, a transfer port adjacent to said inlet port, a passage connecting said ports, means for admitting air only through said inlet port, said air being compressed in said pump chamber and delivered through said passage and transfer port to the working side of said piston, and means for carburetting said air thereafter.
- 10 3. A two-stroke engine, comprising a cylinder, a piston reciprocable in said cylinder, an exhaust valve in one end of said cylinder, an inlet port in the opposite end of said cylinder, a transfer port adjacent to said inlet port, an inlet valve in external communication with both said ports, an injection port in said cylinder, a reservoir for combustible liquid, a pump in communication with said reservoir and delivering to said injection port, a needle-valve controlling the communication with said reservoir, and means for operating said pump to deliver during the movement of said piston towards the first end of said cylinder.
- 15 4. A two-stroke engine, comprising a cylinder, a piston reciprocable in said cylinder, an exhaust valve in one end of said cylinder, an inlet port in the opposite end of said cylinder, a transfer port adjacent to said inlet port, an inlet valve in external communication with both said ports, an injection port in said cylinder, a pump adapted to supply combustible through said injection port, and means for operating said pump to deliver on the exhaust valve side of said piston after said piston has closed said inlet and transfer ports.
- 20 5. A two-stroke engine comprising a cylinder, a piston reciprocable in said cylinder, an exhaust valve in one end of said cylinder, an inlet port in the opposite end of said cylinder, a transfer port adjacent to said inlet port, a chamber connecting said ports, an inlet valve opening into said chamber, a crank shaft rotating in connection with the reciprocation of said piston, crank discs upon said crank shaft, said discs having lateral grooves to form cams, and valve tappets having their extremities engaged in said cam-grooves, said tappets operating said exhaust and inlet valves.
- 25 6. A two-stroke engine comprising a cylinder, a piston reciprocable in said cylinder, an exhaust valve in one end of said cylinder, an inlet port in the opposite end of said cylinder, a transfer port adjacent to said inlet port, a chamber connecting said ports, an inlet valve opening into said chamber, a crank shaft rotating in connection with the reciprocation of said piston, crank discs upon said crank shaft, said discs having lateral grooves to form cams, and valve tappets having their extremities engaged in said cam-grooves, said tappets being positively connected to said exhaust and inlet valves respectively and controlling said valves in both directions by the rotation of said cam discs.
- 30 7. A two-stroke engine, comprising a cylinder, a piston reciprocable in said cylinder, an exhaust valve in one end of said cylinder, an inlet port in the opposite end of said cylinder, a transfer port adjacent to said inlet port, a chamber connecting said ports, an inlet valve opening into said chamber, means for injecting combustible into said cylinder, a crankshaft rotating in unison with the reciprocation of said piston, crank disks upon said crank shaft, having lateral grooves to form cams, and positive means operated by the rotation of said cam-disks for controlling said exhaust and inlet valves and injecting means.
- 35 8. A two-stroke engine, comprising a cylinder, a piston reciprocable in said cylinder, an exhaust valve in one end of said cylinder, an inlet port in the opposite end of said cylinder, a transfer port adjacent to said inlet port, a chamber connecting said ports, an inlet valve opening into said chamber, an injection port in said cylinder, a reservoir for combustible, a fuel-pump in communication with said reservoir and delivering to said injection port, a ported barrel to said pump, said barrel admitting combustible through a port from said reservoir, a valve controlling the opening of said port, and means for positively operating said exhaust and inlet valves and fuel-pump.
- 40 9. A two-stroke engine, comprising a working cylinder, a working piston reciprocable in said cylinder, an exhaust valve in the head end of said cylinder, an inlet port in the opposite end of said cylinder, a transfer port adjacent to said inlet port and in external communication therewith, an external chamber connecting said ports, an inlet valve in said chamber, a guide-cylinder in alignment with said working cylinder, a cover separating said working and guide-cylinders, a dummy piston reciprocable in said guide-cylinder, a piston-rod connecting said working and dummy pistons, said piston-rod passing through said cylinder cover, a packing gland for said piston-rod in said cylinder cover, a crankshaft, a connecting rod between said dummy piston and crank-shaft, cam-disks upon said crankshaft, positive means operated by the rotation of said cam-disks for controlling said exhaust and inlet valves.
- 45 10. A two-stroke engine, comprising a cylinder, a piston reciprocable in said cylinder, an exhaust valve in one end of said cylinder, an inlet port in the opposite end of said cylinder, a transfer port adjacent to said inlet port, a chamber connecting said ports, an inlet valve opening into said chamber, a crank shaft rotating in connection with the reciprocation of said piston, crank discs upon said crank shaft, said discs having lateral grooves to form cams, and valve tappets having their extremities engaged in said cam-grooves, said tappets being positively connected to said exhaust and inlet valves respectively and controlling said valves in both directions by the rotation of said cam discs.
- 50 11. A two-stroke engine, comprising a cylinder, a piston reciprocable in said cylinder, an exhaust valve in one end of said cylinder, an inlet port in the opposite end of said cylinder, a transfer port adjacent to said inlet port, a chamber connecting said ports, an inlet valve opening into said chamber, a crank shaft rotating in connection with the reciprocation of said piston, crank discs upon said crank shaft, said discs having lateral grooves to form cams, and valve tappets having their extremities engaged in said cam-grooves, said tappets being positively connected to said exhaust and inlet valves respectively and controlling said valves in both directions by the rotation of said cam discs.
- 55 12. A two-stroke engine, comprising a cylinder, a piston reciprocable in said cylinder, an exhaust valve in one end of said cylinder, an inlet port in the opposite end of said cylinder, a transfer port adjacent to said inlet port, a chamber connecting said ports, an inlet valve opening into said chamber, a crank shaft rotating in connection with the reciprocation of said piston, crank discs upon said crank shaft, said discs having lateral grooves to form cams, and valve tappets having their extremities engaged in said cam-grooves, said tappets being positively connected to said exhaust and inlet valves respectively and controlling said valves in both directions by the rotation of said cam discs.
- 60 13. A two-stroke engine, comprising a cylinder, a piston reciprocable in said cylinder, an exhaust valve in one end of said cylinder, an inlet port in the opposite end of said cylinder, a transfer port adjacent to said inlet port, a chamber connecting said ports, an inlet valve opening into said chamber, a crank shaft rotating in connection with the reciprocation of said piston, crank discs upon said crank shaft, said discs having lateral grooves to form cams, and valve tappets having their extremities engaged in said cam-grooves, said tappets being positively connected to said exhaust and inlet valves respectively and controlling said valves in both directions by the rotation of said cam discs.

inlet valves, an eccentric upon said crank-shaft, an oil-pump operated by the rotation of said eccentric and supplying lubricant to said crankshaft and guide-cylinder, means

5 for regulating the supply of lubricant to said guide-cylinder, means for collecting lubricant upon said dummy piston, oil-ways through said piston-rod and working piston, and means for forcing lubricant collected by

10 said dummy piston through said oil-ways.

10. A two-stroke engine comprising a cylinder, a shallow piston reciprocable in said cylinder, one end of said cylinder forming the working chamber, said piston having a

15 smooth surface on the side towards said chamber, the other end of said cylinder being of the same diameter as the first and forming the pump chamber, a mechanically operated exhaust valve in said working

20 chamber, an inlet port in said pump chamber, a transfer port adjacent to said inlet port, said ports separated by a distance equal to the depth of said shallow piston, a

25 passage connecting said ports externally of said cylinder, and a mechanically operated inlet valve in said passage, said transfer

port delivering a charge from said pump chamber into said working chamber across the smooth surface of said piston.

11. A two-stroke engine, comprising a cylinder, a shallow piston reciprocable in said

30

cylinder, a hollow piston rod, a mechanically operated exhaust valve at the head end of said cylinder, an inlet port at the opposite end of said cylinder, a transfer port adjacent to said inlet port, said ports separated by a distance equal to the depth of said shallow piston, an external chamber connecting said ports, a mechanically operated inlet valve in said external chamber, radial 40 oil-ways connecting the periphery of said piston to the bore of said hollow piston rod, and means operated by the reciprocation of said piston to force lubricant through said hollow piston rod and radial oil-ways.
